UNITED STATES PATENT OFFICE

2,430,199

FOOTWEAR

Stanley Louis Wilding, Fazakerley, Liverpool,
EnglandApplication August 8, 1944, Serial No. 548,537
In Great Britain August 28, 1943Section 3, Public Law 690, August 8, 1946
Patent expires August 28, 1963

4 Claims. (Cl. 36—36)

1

This invention relates to boots and shoes, but has more especial reference to the heels thereof and protectors, pads, or tread-pieces—which take the usual wear—therefor, of the kind or type in which there are provided inter-engaging parts on the protector, pad or tread-piece (hereinafter, for convenience of reference only, designated "tread-piece") and heel; and my invention has for its object to provide a construction or formation of heel and a tread-piece for application thereto, which latter is of simple and cheap construction, may be quickly applied and removed by an unskilled person, when it is desired to renew same, is not liable to accidental detachment in course of wear, and—if of rubber or like elastic or resilient substance—ensures greater comfort to the wearer than is afforded by tread-pieces of conventional types.

Further, my tread-piece, may, if rubbed down—and so reduced in thickness—on one side in course of wear, be transferred to the other heel of the shoe, thereby prolonging the useful life of the tread-piece.

According to my invention, there are longitudinally formed or provided on the sides of a heel surface of a boot or shoe, a pair of bar-like projections so arranged in relation to each other and configurated that there is created between same a tapering channel, the inner—i. e. opposed—walls whereof are undercut or dovetailed, and said channel being essentially characterised in that its narrower end is at the front of the heel, whilst, its wider end—and so the adjacent ends of said side bars—terminates short of the rear of the heel. And a tread-piece, for application to the heel, comprises, (a) an outer wearing surface, (b) an under part consisting of a middle bar-like member of tapering and undercut or dove-tailed shape complementary to the configuration of said heel channel and adapted to be slid therein from the rear of the heel and interlock with the opposed undercut walls thereof, and a portion extending to the rear of the heel to increase the thickness thereabout of the tread-piece; and (c) means associated with said interlocking bar of the tread-piece whereby the latter may be securely connected by hand to the heel when positioned thereon, and readily freed therefrom for withdrawal when worn, preparatory to the transfer of the tread-piece from one shoe heel to the other, or fitment of a new tread-piece.

Said locking means may comprise a wire rod located in a longitudinal groove formed for its reception in said interlocking bar of the tread-piece and the end portions whereof are reversely

2

bent. One bent inner end or arm of said rod is accommodated and free to move in a covered cavity of the under portion of the tread-piece and provided for its reception, whilst the other—exposed—bent end or arm of the rod is adapted to be turned by the fingers in front of and preferably in contact with the heel, when the tread-piece is applied thereto, and so prevent it from rearward displacement during wear.

10 In one embodiment of my invention, said undercut side bar components of the heel may be formed by appropriately cutting and angularly bending a sheet metal base plate which is screwed or otherwise secured to the flat face of the heel, 15 said angular bendings being reinforced by pieces of suitable strong and rigid material.

I will further describe my invention with the aid of the accompanying sheet of explanatory drawings which illustrate, by way of examples 20 only, two modes of embodying same.

In said drawings,

Fig. 1 is a perspective view of a shoe the heel whereof is constructed for the reception of and has received a detachable tread-piece.

25 Fig. 2 is a front view, Fig. 3 a plan, and Fig. 4 a side elevation, of the heel prior to the fitment of the tread-piece thereto, and Figs. 5, 6 and 7 are, respectively, side elevation, end view, and plan of the tread-piece.

30 Fig. 8 is a detached view of a locking bar detached.

Referring to the drawings:

a indicates a shoe to the heel portion a¹ whereof is secured by screws b a sheet metal plate which 35 has been cut and shaped to provide a base plate c, c¹ and raised angular side bar portions c², c² which are reinforced or strengthened against collapse by blocks d rubber, leather, wood, or any suitable material, which may, if desirable, be secured by nailing, or otherwise.

The exterior edges of said angle bars c² follow the contour of the edge of the heel a¹, whilst the opposed inner walls thereof provide between them a tapering channel e, and are undercut or dove-tailed, as shown. Said channel e has its narrower end at the front of heel a¹, whilst its wider end—and so the adjacent ends of angle bars c²—terminates short of the rear of the heel, leaving a flat part c¹ of the base plate thereabouts.

45 Referring now to the tread-piece, this comprises a wearing surface f and an under portion comprising a tapering and undercut bar g complementary to the heel channel e, and a rear thickness g¹ adapted to coincide with the flat 55 part c¹ of the heel plate c, c¹, so that at this

near—part the tread-piece is of additional thickness which enhances its longevity in use, and if made of rubber, or the like, or leather, a substantial cushion is provided, whereby shock to the wearer during walking is minimized.

Disposed in a longitudinal groove *h* in the tread-piece is the stem portion *j* of a locking member *j*, *j*¹, *j*², composed of wire bent to provide said stem and lateral arms *j*¹, *j*² one, *j*¹ of which projects free of the tread-piece whilst the other arm *j*² is accommodated and free to move in a slot *k* provided in bar *g* for its reception, and said slot *k* being reinforced by a metal plate piece *l*. Said locking member is prevented from displacement by means of a cover strip *m* secured to bar *g*.

In fitting the tread-piece, it is merely necessary to slide same into engagement with heel *a*¹ from the rear of the latter, so that the bar portion *g* of the tread-piece engages the undercut walls of the angle plate *c*². Then the inner arm *j*¹ of locking member *j*, *j*¹, *j*² is turned by hand to move it in front of the heel *a*¹ (Fig. 1) and so prevent the tread-piece from rearward displacement during wear.

To remove the tread-piece it is merely necessary to turn arm *j*¹ to clear the front of the heel and then withdraw the tread-piece from engagement with the undercut walls of the heel's angle plate *c*².

What I claim as my invention and desire to secure by Letters Patent is:

1. A boot or shoe heel at the sides whereof longitudinally are formed or provided a pair of bar-like projections so arranged in relation to each other and configurated that there is created between same a tapering channel the inner—i. e. opposed—walls whereof are undercut or dovetailed, and said channel being characterised in that its narrower end is at the front of the heel, whilst its wider end—and so that adjacent ends of said bars—terminates short of the rear of the heel for the purpose specified.

2. A boot or shoe heel as claimed in claim 1, in which said undercut or dovetailed side bars are formed of plate metal secured to the heel.

3. In combination with or for detachable ap-

plication to a boot or shoe heel as claimed in claim 1, a tread-piece comprising an outer wearing surface; an under part consisting of a middle bar-like member of tapering and undercut or dovetailed shape complementary to the configuration of the channel provided on the boot or shoe heel, and adapted to be slid therein from the rear of the heel and interlock with the opposed under cut walls thereof, and having a portion extending to the rear of the heel to increase the thickness thereabout of the tread-piece; and means associated with the said interlocking bar of the tread-piece whereby the latter may be securely connected by hand at the front of the heel when positioned thereon, and readily freed therefrom for withdrawal when worn preparatory to its transfer from one shoe heel to the other, or fitment of a new tread-piece.

4. In combination with or for detachable application to a boot or shoe heel as claimed in claim 1, a tread-piece comprising an outer wearing surface; an under part consisting of a middle bar-like member of tapering and undercut or dovetailed shape complementary to the configuration of the channel provided on the boot or shoe heel, and adapted to be slid therein from the rear of the heel and interlock with the opposed under cut walls thereof, and having a portion extending to the rear of the heel to increase the thickness thereabout of the tread-piece; and tread-piece securing means associated with said interlocking bar, comprising a revolvably located rod bent or shaped to provide reversely bent end portions or lateral arms one of which is adapted to be turned by hand in front of the heel, whilst the other arm is operable in a recess provided for its reception in the tread-piece.
